SPECTACLE FRAME

Frances R. Nesselroth, Flushing, N. Y., assignor
to Globe Ring Co., Brooklyn, N. Y., a firm

Application December 13, 1948, Serial No. 150,124

Term of patent 3½ years

(Cl. D57—1)

To all whom it may concern:

Be it known, that I, Frances R. Nesselroth, a citizen of the United States of America and resident of Flushing, County of Queens, and State of New York, have invented a new, original, and ornamental Design for a Spectacle Frame, of which the following is a specification, reference being had to the accompanying drawing, forming a part thereof, in which

Fig. 1 is a front elevational view of a spectacle frame embodying my design,

Fig. 2 is a top view thereof, and

Fig. 3 a side view.

The essential features of my design for a spectacle frame reside in a specific type of ornamentation shown thereon and the placement of the same, as seen most clearly in Fig. 1.

I claim:

The ornamental design for a spectacle frame as shown and described.

FRANCES R. NESSELROTH.
